UNITED STATES PATENT OFFICE.

JAMES F. MC GUIRE, OF NEW YORK, N. Y.

DESIGN FOR A BOTTLE.

SPECIFICATION forming part of Design No. 36,672, dated December 8, 1903.

Application filed November 6, 1903. Serial No. 180,141. Term of patent 7 years.

To all whom it may concern:

Be it known that I, JAMES F. MC GUIRE, a citizen of the United States, residing in New York, borough of Brooklyn, in the State of New York, have invented and produced a new, original, and ornamental Design for Bottles, of which the following is a specification.

The nature of my design is fully represented in the accompanying drawing, to which reference is made and in which a bottle embodying my design is shown in elevation.

I claim as my invention—
The ornamental design for a bottle, substantially as shown.

In testimony that I claim the foregoing as my invention I have signed my name in presence of two subscribing witnesses.

JAMES F. MC GUIRE.
